UNITED STATES PATENT OFFICE.

DANIEL HOFFMAN, OF POTTSVILLE, PENNSYLVANIA.

IMPROVEMENT IN PENCIL-SHARPENERS.

Specification forming part of Letters Patent No. 129,956, dated July 30, 1872.

To all whom it may concern:

Be it known that I, DANIEL HOFFMAN, of Pottsville, in the county of Schuylkill and State of Pennsylvania, have invented a new and valuable Improvement in Pencil-Sharpener; and I do hereby declare that the following is a full, clear, and exact description of the construction and operation of the same, reference being had to the annexed drawing making a part of this specification, and to the letters and figures of reference marked thereon.

Figure 1 of the drawing is a representation of a front view of my invention. Fig. 2 is a plan view of the same on an enlarged scale. Fig. 3 is a front view with plate E removed. Figs. 4, 5, and 6 are details.

This invention has relation to lead-pencil sharpeners; and the novelty consists in the combination, with a hollow conical knife for shaping the wood, of a rough surface inclosed between metal lips, and used for the purpose of pointing and finishing the lead, as hereinafter described.

Referring to the drawing, A represents a strip of metal, having one of its ends bent to form a hollow cone, a, with a longitudinal opening at b. B designates a knife, secured to the strip or plate A, its edge entering the cone through the opening b. The knife is slotted at c, to render it adjustable, and is secured by screws d, so that it may be removed for the purpose of being sharpened. E represents a plate, covering the knife, and held by the screws d. Said plate is designed for the purpose of preventing the knife from becoming loose, but does not form an essential element of my invention. F represents a strip or plate of metal secured to the back part of the plate A at a distance therefrom sufficient

to admit of the arrangement of two pieces of emery-paper, d¹, or their equivalent between them. A part of the strip F is slightly bent outward, so as to produce a tapering space. The edge of the strip F, on a line with the point of the cone, may be flanged, so as to overlap the edge of the strip A.

After the end of the pencil has been cut in the cone, the pencil is to be taken hold of near the point by the thumb and fore-finger, and the projecting lead inserted between the pieces of emery-paper, and, by proper manipulation, finished off to as fine a point as may be desired. The point may be made either wedge-shaped or conical, according to the manner in which it is moved between the rough surfaces.

Between the emery-paper and the plates A F pieces of soft cloth d² or other cushion-like material may be advantageously placed. The effect will be to allow the emery-paper to give, and thus prevent the lead from being broken. When the emery-paper becomes worn and useless, it may be replaced by new material, the plate F being, for this purpose, removed by loosening the screw e.

I claim as my invention—

The lead-pencil sharpener, consisting of the plate A, bent at one end into conical form, the slotted adjustable knife B, screws d e, the bent plate F, having oblique inner edge, and the cushioned emery-leaves d¹, substantially as shown and described.

In testimony that I claim the above I have hereunto subscribed my name in the presence of two witnesses.

DANIEL HOFFMAN.
